Letter Patent No 3086, dated Feb 18, 1865.

Design for the Plates of a Books Store.

The Schedule referred to in these Letters Patent and making part of the same.

To all whom it may concern:

Be it known, that I, William W. Stevens of the City of Portland, County of Cumberland and State of Maine, have invented a new and original design for a Books Store which I term the Criterian and I do hereby declare that the following is a full and exact description of the same, referring had to the accompanying drawings and to the letter of reference theron. Of the said drawings Figure 1 denotes a perspective elevation of my design, and exhibits the top, front, side and back of the store with their doors, also the legs. Figure 2 represents a vertical section of the top A. door B. and side C. taken through the line O'D. Figure 3 represents a vertical section of the top A. front B. front door C. hearth E. ash pit F. through the line A. B. In said drawings F represents the door of the oven, G represents the end door of the fire box, H represents the front door to the legs.

I claim the configurations and ornaments above described, and shown in the drawings as a design for a Books Store.

In testimony whereof I have hereunto set my hand and seal this the twenty sixth day of January A. D. 1865.
